UNITED STATES PATENT OFFICE.

FREDERICK A. PARKER, OF GARDNER, MASSACHUSETTS.

IMPROVEMENT IN TILTING-CHAIRS.

Specification forming part of Letters Patent No. 137,091, dated March 25, 1873.

To all whom it may concern:

Be it known that I, FREDERICK A. PARKER, of Gardner, in the county of Worcester and Commonwealth of Massachusetts, have invented certain new and useful Improvements in Tilting-Chairs; and I do hereby declare the following to be a full, clear, and exact description of the same, reference being had to the accompanying drawing which forms a part of this specification, and in which—

Figure 1 represents a side view of a chair having my invention applied thereto, the seat being shown in a horizontal or level position. Fig. 2 represents a side view of the chair, the seat being shown tilted up in front; and Fig. 3 represents a vertical central section of the chair, as shown in Fig. 1.

To enable those skilled in the art to which my invention belongs to make and use the same, I will proceed to describe it in detail.

In the drawing, the part marked A is the seat of the chair, to which are fastened two curved or convex supports or runners, B B, which fit and rest upon corresponding curved or concave parts C C, fastened to the legs D of the chair. The parts B B and C C are connected by rounds *a a* and *b b*, respectively. To the inner sides of the parts C C are fastened metal guide-pieces *c*, having curved slots *d*, which correspond with the curve of the parts B C, and screws *e* are passed through these slots into the parts B B, whereby the seat and its supporting-frame are retained in their proper relative positions when the chair is in use. In lieu of the plates and screws the parts B C may be fitted to work together by means of projections and grooves, or flanges

may be made on one or both of the parts to lap by the other, thereby retaining the parts in proper position.

It will be seen that the chair-back, when the front is tilted up, is moved forward, consequently is not liable to strike against the side of the wall or partition of the house or office in which it may be used. The parts are not liable to break or get out of order, while the chair is both strong and can be made quite cheaply.

The friction between the parts B and C is sufficient to retain the parts in any adjusted position; but, if preferred, a holding-catch could be combined with the chair for such a purpose.

Those who have experienced the objections to the many different styles of tilting-chairs heretofore in use, both as regards the complication of parts, expense, and liability of the back striking against the walls, when used near them, will readily appreciate the advantages of my invention.

Having described my improvements in tilting-chairs, what I claim therein as new and of my invention, and desire to secure by Letters Patent, is—

A tilting-chair consisting of a seat-portion provided with convex curved parts B B, in combination with a supporting-frame or base provided with concave parts C C, curved to correspond with the parts B B, said parts fitting and operating together substantially as shown and set forth.

FREDERICK A. PARKER.
